UNITED STATES PATENT OFFICE.

ELBERT L. HYDE, OF CLEVELAND, OHIO, ASSIGNOR OF ONE-HALF TO WILLIAM DUNHAM, OF BARBERTON, OHIO, AND ONE-HALF TO COLUMBIA CHEMICAL COMPANY, OF BARBERTON, OHIO, A CORPORATION OF PENNSYLVANIA.

HAND-TRUCK.

1,365,106.

Specification of Letters Patent. Patented Jan. 11, 1921.

Application filed January 21, 1920. Serial No. 353,019.

To all whom it may concern:

Be it known that I, ELBERT L. HYDE, a citizen of the United States, residing at Cleveland, in the county of Cuyahoga and State of Ohio, have invented certain new and useful Improvements in Hand-Trucks, of which the following is a specification.

This invention relates to hand trucks, and is an improvement upon the hand truck 10 shown, described and claimed in a prior application filed December 26, 1919, by William Dunham, for hand trucks.

Said prior Dunham application illustrates a truck adapted particularly for use in handling barrels, drums or like articles and so arranged that the truck can be upended into nested relation with a drum standing on end and then tilted with the drum, whereupon certain toes or engaging members are 20 moved in beneath the lower end of the drum to support it on its seat thereon.

The object of the present invention is to improve the operating mechanism for said supporting or engaging toes or members to 25 enable them to be more easily operated and particularly to cause them to be actuated either simultaneously with or as the result of the tilting movement of the truck, to thereby do away with the necessity of hand 30 manipulation of said members and leave the operator's hands free for taking care of the truck and load.

Further objects of the invention are in part obvious and in part will appear more 35 in detail hereinafter.

The invention comprises the construction and arrangement of parts hereinafter described and claimed.

In the drawings, which represent one suitable embodiment of the invention, Figure 1 40 is a side elevation, showing the truck upended in nested relation with a drum; Fig. 2 is a rear view of the truck; Fig. 3 is a sectional plan view on the line 3—3, Fig. 1; Fig. 4 is a detail side elevation, illustrating 45 a modification; Fig. 5 is a side elevation, on a larger scale, illustrating the operating mechanism at the lower end of the left hand side frame member in Fig. 1, part of a cover 50 plate being omitted for clearness of illustration; Fig. 6 is a front view, or a view from the left in Fig. 5, parts being broken away and in section; Fig. 7 is a sectional plan view on the line 7—7, Fig. 5; and Fig. 8 is a view

corresponding to Fig. 5 and showing the truck in tilted position.

The truck shown in the drawings comprises a suitable frame of the same general form illustrated in said prior Dunham application. Said frame includes two parallel side members 1 formed of channel sections and each provided at one end with an operating handle member 2. The side members are connected by suitable cross braces 3, three of which are shown, and each of which 65 comprises a curved inner or front member 4 and a rear substantially straight member 5, said members being suitably connected to the side frame parts and to each other if necessary by rivets, bolts or the like. The 70 front members 4 are curved on the arc of a circle, the diameter of which is the diameter or approximately so, of the drum, barrel or other article 6 to be manipulated by the truck and the several inner members 4 together form a concave seat for said article. The curvature of members 4 is such that the 75 bottom of said seat, indicated at 7, Fig. 3, is in a transverse plane parallel with and passing through the rear edges 8 of the truck 80 frame side members, or at least said members are so curved that the bottom of said seat is behind or in rear of the heel of the truck, as will later appear. The truck frame is also provided with suitable supports 9 for 85 the axle 10 on which are located the wheels 11. These wheels are of such size and axle 10 is so located that when the truck is upended, as in Fig. 1, the wheels lie an appreciable distance above the level of the floor 90 or other support.

Toward its handle end the truck frame is provided, near the bottom of the concave drum seat therein, with suitable means for engaging the upper end of the drum or other article to be handled. This engaging means may be of any well known or suitable description, such as a chain fastened to the frame and adapted to surround the upper end of the drum or may be of the form 95 shown in said prior Dunham application, to-wit, a latch 12 provided with a handle 13 and pivoted at 14 to a cross brace, said latch being provided with a hook portion 15 adapted when the latch is moved down to the 100 position shown in the drawings to embrace a part of the cross brace and also the drum chime 16. Fig. 4 shows another arrangement 105

in which the holding means comprises a hook 17 at one end of a chain or cable 18 fastened to a cross brace 19 connecting the usual legs 20 which support the truck when 5 in horizontal position on the floor.

Each of the side members of the truck frame is provided at its wheel end with a movable drum engaging member so arranged as to be capable of being moved into 10 engaging or supporting position beneath the lower end of a drum when the latter is tilted, and the truck frame is also provided with suitable actuating means for said members preferably so arranged as 15 to cause actuation there either simultaneously with or as the result of the tilting movement of the truck. The mechanisms at the wheel ends of the two side frame members are identical except that one is a right 20 and the other is a left so that description of one will suffice for both.

Each engaging member comprises an arm or lever 21 pivoted at 22 and provided with a toe portion 23 movable through an opening 24 in the front portion of the frame member. The two members 21 may be actuated simultaneously with or during tilting motion of the truck by pressure applied by the foot to a bail or U-shaped member 25 coupling or connecting said levers 21 and which bail extends rearwardly from the frame. However, to avoid any necessity for attention by the operator, each side frame member is provided with means actuated by 30 tilting movement of the truck and operatively connected to said levers 21. The means shown comprises a member 26 having a shoe portion 27 resting on the floor, said member being pivoted at 28 and being 35 provided with an upwardly extending arm 29. Each lever 21 is provided with a pair of rearwardly extending ears 30 having curved slots 31 to receive the ends of a pin 32 in the arm 29. Member 26 also has a 40 rearwardly extending portion 33 which closes the opening at the rear of the side frame member so as to prevent the entrance of foreign matter thereinto. The mechanism is inclosed and protected by a cover 45 plate 34.

Fig. 5 shows the normal position of the parts. The lever 21 is retracted and only a small portion of the toe 23 extends through the opening 24, this portion being 50 beveled or inclined laterally, as at 23^a, so that it will substantially form a continuation of the concave drum seat and nest closely with the drum when the truck is applied thereto, as in Fig. 1. The axes or 55 pivots 28 of the members 26 are located in front of the bottom of the concave seat, and more specifically are shown as being located about midway between the front and rear edges of the side frame members. These 60 pivots are the pivots upon which the truck 65

turns while being tilted and essentially form what may be called the "heel" of the truck. In rear of said heel the lower ends of the side frame members are cut off on an incline, as indicated at 35.

When the truck is tilted backwardly away from its normal vertical position the first effect is to tilt the truck relatively to the members 26, which rest solidly and immovably upon the floor, until the parts reach 70 the dotted line position, Fig. 1. During this first motion there is no movement of members 21, as the pins 32 ride idly along the slots 31. During the same motion, however, the barrel or drum, which rests on the 75 floor and turns about a transverse axis at the bottom of the concave seat in effect moves upwardly along the truck, approaching the position shown in dotted lines, Fig. 8. Therefore the important effect is to 80 move the toes 23 downwardly to a position below the bottom of the drum. By this time the pins 32 have reached the front ends of slots 31, so that additional tilting movement of the truck causes the arms 29 to advance the levers 21 and move them to the 85 position shown in Fig. 8, in which position the toes 23 have been introduced or projected into engaging or holding position beneath the lower end of the drum. Fig. 8 90 shows the final position of the parts just before the wheels 11 touch the floor. Further tilting movement of the truck engages the wheels with the floor and lifts the side frame members with the drum supported 95 thereon from the floor.

The drum is deposited in upended position in its new location by reverse operations. As the drum is tilted toward vertical position the members 26 engage the floor and 100 withdraw members 23 from beneath the drum and finally reach the position shown in Fig. 5. In the operation of tilting the truck toward the vertical the drum strikes the floor first and is pushed upwardly on the 105 truck a slight amount to free it from the holding members 23 so that the latter are readily withdrawn.

In the position shown in Fig. 8 pressure applied to the members 21 will not push 110 them backwardly to normal position, as the pins 32 will wedge in the ends of the slots 31, the arrangement in this position being in effect a toggle. Therefore, when the holding members are extended they are in effect 115 locked and can only be retracted by operation of members 26. In a similar manner the parts are locked in retracted position, as shown in Fig. 5, the locking effect being due 120 in both instances to the presence of the 125 slots 31.

Members 26 with their arms 29 may be wholly omitted and the members 21 operated by the bail 25, but if the members 26 are utilized the bail 25 may be resorted to for 130

producing extra pressure to move members 21. Bail 25 has the more important function of coupling together the holding members 23 on the two sides of the truck frame so 5 that both of them are compelled to operate in unison at all times.

What I claim is:

1. A hand truck provided with a frame and wheels thereon, said frame being formed 10 to provide a seat for an article, and means on said frame actuated by tilting movement of the truck and thereby movable into said seat beneath an article tilted with the truck.

2. A hand truck, comprising a frame having parallel side members and provided with wheels, said side frame members near their wheel ends being provided with article engaging means, and means actuated by tilting movement of the truck for operating said 20 members.

3. A hand truck, comprising a frame provided with wheels and a seat for an article, means near the wheel end of said frame for entering said seat and engaging the lower 25 end portion of an article therein, and means whereby movement of the truck frame actuates said article engaging means.

4. A hand truck, comprising a frame provided with wheels near one end, article engaging means near each end of the truck, 30 and means actuated by movement of the truck for operating the means near the wheel end.

5. A hand truck, comprising a frame provided with an article receiving seat, means 35 near one end of said truck for entering said seat to engage an article therein, and operating means therefor engaging the floor when the truck is upended thereon.

6. A hand truck, comprising a frame having side members, wheels thereon, oscillating article engaging members mounted one on each side frame member, and a bar coupling 40 said oscillating members to move together.

7. A hand truck, comprising a frame having side members, wheels thereon, oscillating article engaging members mounted one on each side frame member, a bar coupling said 45 oscillating members to move together, and floor engaging means adapted to actuate said 50 swinging members.

In testimony whereof I affix my signature.

ELBERT L. HYDE.
